GOVERNOR

Marion Mallory, Detroit, Mich.

Application November 6, 1942, Serial No. 464,821

9 Claims. (Cl. 290—40)

This invention relates to a governor for an internal combustion engine arranged to drive an electric generator.

It is the object of the invention to produce a governor for an internal combustion engine-electrical generator outfit which operates efficiently and which is cheaper to fabricate than other governors for the same purpose now on the market.

The invention contemplates a governor which will admit more charge to the engine when more electrical load is added to the generator and which will decrease the amount of charge admitted to the engine when the electrical load on the generator is decreased.

Fig. 1 is a diagrammatic showing of the motor generator assembly.

Fig. 2 is a detail of the governor mechanism for the motor generator assembly.

Fig. 3 shows a modified form of the invention.

The electrical generator is designated 1. Generator 1 is preferably a direct current generator but the invention is also useful with an alternating current generator.

The electrical output circuit of the generator comprises wires 2 and 3. Devices 4, 5, 6, 7 and 8 (shown schematically in Fig. 2) are connected into the output circuit of the generator. Electrical devices 4 through 8 can be any device which is operated by electrical current such, for example, as incandescent lamps or electric welders for either resistance or arc electrical welding.

The generator 1 is arranged to be driven by the internal combustion engine 9 which can be either an injection engine or a carburetted engine. The engine 9, by way of example, is shown as a carburetted engine having a carburetor 10 provided with an intake passageway 11, an air inlet 12, a fuel charge outlet 13, a venturi 14 and a fuel nozzle 15 for the gasoline or other hydrocarbon fuel. The carburetor is provided with the usual throttle valve 16 mounted upon shaft 17 journalled in the carburetor housing. An arm 18 is fixed on the shaft 17 outside the carburetor housing. A tension spring 19 has one end fixed to the arm 18 and the other end to lug 20 on the outside of the carburetor housing and tends to open the throttle valve 16.

A suction device comprising a flexible diaphragm 21 mounted within a housing 22 is connected to arm 18 by link 23. The suction device 22 is connected to conduit 24. Conduit 25 connects conduit 24 with orifice 26 in the intake passageway on the engine side of throttle valve 16 and conduit 27 connects conduit 24 with orifice

28 in the venturi 14. As stated above, one end of conduit 24 is connected into the housing 22 of the suction device and the other end of the conduit 24 communicates with atmosphere. However, the communication of conduit 24 with atmosphere is controlled by a solenoid valve 29 reciprocably mounted in housing 30. Conduit 24 connects into housing 30 and housing 30 is connected by conduit 31 into the intake passageway of the carburetor above the venturi.

Valve housing 30 can open directly into atmosphere, but as shown communicates with atmosphere indirectly through conduit 31 and intake passageway of the carburetor merely to obtain cleaner air, it being customary to provide the intake end of the carburetor with an air cleaner. Valve 29 is a metering type of valve and therefore is provided with a tapered flat surface 32 which cooperates with the orifice 33 into which conduit 24 connects to increase the amount that the orifice 33 is opened as the valve 29 rises in the housing 30. Valve 29 is provided with an enlarged steel head 34 which comprises the core of the solenoid. Compression spring 35 tends to keep valve 29 in closed position with respect to orifice 33. The winding for the solenoid valve is designated 36. It is understood that the solenoid can be located in any circuit wherein the current increases as load is applied to the generator and wherein the current decreases as the load on the generator decreases. As shown, for purposes of description only, the solenoid winding 36 is connected into the output line 2 of the generator.

The operation of the motor generator assembly is as follows: At idle position valve 29 will close port 33 thereby shutting off conduit 24 from atmosphere (Fig. 2). At this time the manifold vacuum will be high, spring 19 will be extended, and throttle valve 16 in idle position as shown in Fig. 2. Now if electric light 4 is turned on, current will flow through solenoid 36 and thereby raise piston 34 and valve 29 against spring 35 which is compressed thereby opening orifice 33 and conduit 24 which bleed air into the suction device 22. Due to the fact that flat face 32 on valve 29 is tapered downwardly and inwardly the amount that orifice 33 is opened will increase as valve 29 rises.

When suction device 22 is thus bled to atmosphere the vacuum therein decreases, spring 19 contracts and throttle valve 16 moves toward an open position to permit more charge to be drawn into the engine. If light 5 is now also turned on, more current will pass through the solenoid thereby raising valve 29 further and bleeding

more air into the suction device to thereby cause the throttle 16 to open further. If welders 6, 7 and 8 are now connected into the circuit, in fact if enough load is connected into the circuit 2, 3, still more current will flow through solenoid 36 and thereby operate as above described to fully open valve 29 and completely bleed suction device 22 to atmosphere whereupon spring 19 will open the throttle valve wide as shown in Fig. 3.

If welder 8 were now turned off, less current would flow through solenoid 36, piston 34 would drop slightly or be forced downwardly by spring 35 and partly close orifice 33 and cut down the air bleed to the suction device 22. Thus, the increase in vacuum in suction device 22 would cause diaphragm 21 to move to the right (Fig. 2) against spring 19 and move the throttle valve 16 toward closed position to decrease the charge flowing to the engine.

If all the lights and electric welders were turned off, no current would flow through the solenoid and spring 35 would close valve 29 and shut off the air bleed to the suction device 22. The vacuum would increase in the suction device and throttle valve 16 would move toward fully closed position and slow down the engine to idle.

The modified form of the invention, shown in Fig. 3, is identical with that shown in Figs. 1 and 2 except that a centrifugal valve is connected into conduit 24 to shut off the same from atmosphere whenever the engine reaches a predetermined speed. This centrifugal valve comprises a housing 40 in which is rotatably mounted a shaft 41. The shaft 41 is adapted to rotate in accordance with the speed of the engine and for convenience is the shaft of the engine distributor. Shaft 41 is provided with a hollow cylindrical portion 42 which communicates through orifice 43 with the interior 44 of housing 40. Orifice 43 is controlled by a centrifugally operated valve 45 normally retained in open position by tension spring 46. Valve 45 is fixed on a piston 47 slidably mounted inside cylinder 42. Piston 47 is grooved as at 48 to permit air flow by the piston. The tension of spring 46 is regulated by adjusting screw 49 carried by cylinder 42. The interior of cylinder 42 communicates with conduit 24 by means of axial passageway 50, diametrical passageway 51 and the circular passageway 52 extending completely about shaft 41 and formed by mounting upper support bushing 53 in spaced relation with the lower support bushing 54 for the shaft 41. Housing 40 is connected to orifice 33 by conduit 56.

As shown in Fig. 3 the electrical devices 4 through 8 are in operation. Accordingly centrifugal valve 45 is open, throttle valve 16 is wide open and the engine is operating under full load at a predetermined desired top speed. Now, if for any reason the engine should exceed this predetermined governed speed, centrifugal valve 45 is set to close whenever the engine exceeds a predetermined desired or governed speed. When centrifugal valve 45 closes, conduit 24 is cut off from atmosphere even though valve 29 is wide open and the vacuum will build up in suction device 22 thereby moving the throttle valve toward closed position to slow down the engine. The engine might very well tend to exceed its predetermined top speed in case the instrumentalities 4 through 8 were turned off and for some reason or other valve 29 would not move toward closed position. Hence, even though valve 29 should fail to operate to throttle down the engine,

the centrifugal governor valve will come into play and throttle down the engine to maintain it within its predetermined governed range of speed. Whenever the engine speed falls below its top governed speed, spring 46 will open valve 45 thereby permitting the suction device to communicate with atmosphere (provided valve 29 is open) through conduit 24, passageway 50, orifice 43, chamber 44, conduit 56, orifice 33 and conduit 31.

I claim:

1. In combination with an internal combustion engine having an intake passageway and an electrical generator arranged to be driven by the engine, of a governor comprising a valve in said passageway, a suction device, a conduit connecting said suction device into the intake passageway on the engine side of said valve whereby the suction device moves the valve toward closed position as the vacuum in the suction device increases and moves the valve toward open position as the vacuum decreases, an air bleed for said suction device, and means coordinated with said generator and air bleed means and responsive to an increase in the load put on the generator for moving the air bleed toward open position correspondingly as the load is increased and thereby correspondingly decreasing the vacuum in said suction device whereby the governor valve moves correspondingly toward open position.

2. In combination with an internal combustion engine having an intake passageway and an electrical generator arranged to be driven by the engine, of a governor comprising a valve in said passageway, a suction device, a conduit connecting said suction device into the intake passageway on the engine side of said valve whereby the suction device moves the valve toward closed position as the vacuum in the suction device increases and moves the valve toward open position as the vacuum decreases, an air bleed for said suction device, and means for controlling said air bleed and connected into the generator output circuit and responding to an increase in current flowing therethrough to move the air bleed toward open position correspondingly as said current increases and thereby correspondingly decrease the vacuum in said suction device whereby the governor valve moves correspondingly toward open position.

3. In combination with an internal combustion engine having an intake passageway and an electrical generator arranged to be driven by the engine, of a governor comprising a valve in said passageway, a suction device, a conduit connecting said suction device into the intake passageway on the engine side of said valve whereby the suction device moves the valve toward closed position as the vacuum in the suction device increases and moves the valve toward open position as the vacuum decreases, an air bleed to atmosphere for said suction device including a valve for opening and closing said air bleed, and electrical means responsive to load conditions of the generator for moving the air bleed valve toward open position correspondingly as the load on the generator increases and for moving the air bleed valve toward closed position correspondingly as the load on the generator decreases whereby the suction device moves the governor valve correspondingly toward open position as the load on the generator increases and moves the governor valve correspondingly towards closed position as the load on the generator decreases.

4. In combination with an internal combustion engine having an intake passageway and an

electrical generator arranged to be driven by the engine, of a governor comprising a valve in said passageway, a suction device, a conduit connecting said suction device into the intake passageway on the engine side of said valve whereby the suction device moves the valve toward closed position as the vacuum in the suction device increases and moves the valve toward open position as the vacuum decreases, an air bleed to atmosphere for said suction device including a valve for opening and closing said air bleed, and a solenoid connected into the generator output circuit for operating said air bleed valve, said solenoid responding to an increase in current flowing through the circuit to move the air bleed valve toward open position correspondingly as the current increases and thereby correspondingly decrease the vacuum in said suction device whereby the governor valve moves correspondingly toward open position.

5. In combination with an internal combustion engine having an intake passageway and an electrical generator arranged to be driven by the engine, of a governor comprising a throttle valve in said passageway, a fuel inlet orifice into the intake passageway on the atmosphere side of the said throttle valve, a suction controlled device, a conduit connecting said suction device into the intake passageway on the engine side of said valve whereby the suction device moves the valve toward closed position as the vacuum in the suction device increases and moves the valve toward open position as the vacuum decreases, an air bleed for said suction device, and means connected into the generator output circuit and responding to an increase in current flowing therethrough to move the air bleed toward open position correspondingly as the current increases and thereby correspondingly decrease the vacuum in said suction device whereby the governor valve moves correspondingly toward open position and increases the charge flowing into the engine.

6. In combination with an internal combustion engine having an intake passageway and an electrical generator arranged to be driven by the engine, of a governor comprising a valve in said passageway, a suction device, a venturi in the intake passageway on the atmosphere side of the valve, a conduit connecting the suction device into the venturi, a conduit connecting said suction device into the intake passageway on the engine side of said valve whereby the suction device moves the valve toward closed position as the vacuum in the suction device increases and moves the valve toward open position as the vacuum decreases, an air bleed for said suction device, and means connected into the generator output circuit and responding to an increase in current flowing therethrough to move the air bleed toward open position correspondingly as said current increases and thereby correspondingly decrease the vacuum in said suction device whereby the governor valve moves correspondingly toward open position.

7. In combination with an internal combustion engine having an intake passageway and an

electrical generator arranged to be driven by the engine, of a governor comprising a valve in said passageway, a suction device, a conduit connecting said suction device into the intake passageway on the engine side of said valve whereby the suction device moves the valve toward closed position as the vacuum in the suction device increases and moves the valve toward open position as the vacuum decreases, an air bleed for

10 said suction device, and means connected into the generator output circuit and responding to an increase in current flowing therethrough to move the air bleed toward open position and thereby decrease the vacuum in said suction de-

15 vice whereby the governor valve moves toward open position, and a centrifugal valve operated in accordance with the engine speed for closing off said air bleed whenever the engine reaches a predetermined speed.

20 8. In combination with an internal combustion engine having an intake passageway and an electrical generator arranged to be driven by the engine, of a governor comprising a valve in said passageway, a suction device, a conduit connecting said suction device into the intake passageway on the engine side of said valve whereby the suction device moves the valve toward closed position as the vacuum in the suction device increases and moves the valve toward open position as the vacuum decreases, an air bleed to atmosphere for said suction device, and electrical-

25 ly operated means responsive to an increase in the load put on the generator for moving the air bleed toward open position whereby the governor valve moves toward open position, and centrifugally operated means operated in accordance with the speed of the engine for shutting off said air bleed when the engine reaches a pre-

30 determined speed irrespective of the load on the generator.

35 9. In combination with an internal combustion engine having an intake passageway and an electrical generator arranged to be driven by the engine, of a governor comprising a valve in said passageway, a suction device, a conduit connecting said suction device into the intake passageway on the engine side of said valve whereby the suction device moves the valve toward closed position as the vacuum in the suction device increases and moves the valve toward open position as the vacuum decreases, an air bleed for said suction device in the form of a conduit lead-

40 ing from the suction device to atmosphere, an electrically operated valve responsive to an in-

45 crease in the load put on the generator for closing off the air bleed conduit from atmosphere whereby the governor valve moves toward open position, and a centrifugally operated valve also connected into said air bleed conduit operated in accordance with the speed of the engine for clos-

50 ing said air bleed conduit off from atmosphere irrespective of the load put on the generator and irrespective of the first mentioned electrically operated valve whenever the engine reaches a predetermined speed.

MARION MALLORY.
